UNITED STATES PATENT OFFICE.

WILLIAM S. LANEY, OF LITHOPOLIS, OHIO.

WASHING-MACHINE.

SPECIFICATION forming part of Letters Patent No. 507,711, dated October 31, 1893.

Application filed June 16, 1893. Serial No. 477,833. (No model.)

To all whom it may concern:

Be it known that I, WILLIAM S. LANEY, a citizen of the United States, residing at Lithopolis, in the county of Fairfield, State of Ohio, have invented certain new and useful Improvements in Washing-Machines; and I do hereby declare the following to be a full, clear, and exact description of the invention, such as will enable others skilled in the art to which it appertains to make and use the same.

This invention relates to washing machines which may embody in their organization a heating apparatus for bringing the water to the required temperature or not as desired.

The object of the invention is to facilitate the process of washing clothes and enable the different steps to be performed in the suds box without necessitating the removal or handling of the clothes until ready for hanging out to dry.

The improvement consists of the novel features and the peculiar construction and combination of the parts which will be herein-after more fully described and claimed and which are shown in the annexed drawings, in which—

Figure 1 is a perspective view of the invention. Fig. 2 is a side elevation of the machine as seen from the side provided with the gearing or roller actuating mechanism. Fig. 3 is a longitudinal section of the machine, taken on a line about midway between the sides.

The suds box A may be of any desired construction and is supported on legs a. A series of rollers B are located near one end of the suds box and disposed in approximately a circle and are journaled at their ends in the sides of the suds box. One journal of these rollers is extended beyond the side of suds box and is provided with a sprocket pinion b to be engaged by a sprocket chain C by means of which the said rollers are rotated on their journals or axes. The rollers B are arranged in parallel relation and close together so as to retain clothing that may be placed in the space inclosed by the said rollers. The upper portion inclosed by the said rollers B is left open or unobstructed to permit of the rotary rubber D and the clothing being readily inserted in or removed from the said space. These rollers may be plain or cor-

rugated, or of any of the usual forms common in this class of machines. The rotary rubber D is composed of a central shaft d, heads d' at the ends of the shaft d and provided with journals, and a series of rollers d² disposed in a circle around the shaft d and journal in their ends in the heads d'. This rotary rubber D is journaled at its ends in arms e which are pivotally connected at their upper ends to levers E which in turn have pivotal connections to standards projected vertically from the ends of the suds box. The free ends of the levers E are connected together by a cross bar e' by means of which the levers are operated to manipulate the rotary rubber D. A strap or elastic connection F is attached at one end to the cross bar e' and is adapted to have its other end connected with the suds box to hold the rotary rubber D in operative relation with the rollers B when the machine is in operation. Coil springs G are interposed between the levers E and the arms e to press the rotary rubber D against the rear rollers B so as to leave a space between the forward rollers B and the front side of the rotary rubber to receive the clothing.

The several rollers B constitute a roller bed to receive and support the clothing during the process of washing and each of these rollers B is positively rotated by suitable gearing, as the endless sprocket chain C and the sprocket pinion b herein specified. The sprocket chain C passes over a master sprocket wheel H which is journaled to a side 8c of the suds box and a bracket attached to the said side. This sprocket wheel H is provided with a crank h by means of which the sprocket chain and rollers B are driven in the usual manner as will be readily understood. The rotary rubber D is rotated by its engagement with one or more of the rollers B and is free to move to adapt itself to the bulk of clothing between it and the said rollers B.

A heater K is attached to the bottom of the suds box and is of usual construction, being designed as a convenient means for heating the water in the suds box. A pipe k connects the bottom of the suds box with the said heater. A short pipe k' provided in the side 100 of the suds box and closed by a stopper admits of the dirty water being drawn off from

the suds box when it is desired to supply the same with clear or fresh water as is necessary in the process of washing.

The operation of the machine is as follows:

- 5 The suds box being supplied with the proper water and the rollers B being rotated in the manner herein set forth, the clothing to be cleansed is placed in the space inclosed by the said rollers and is agitated or set in motion by the rotation of the said rollers B. The rotary rubber D pressing against the clothing and rotated from the said rollers B in the manner set forth, causes the clothing to rotate with the said rotary rubber and effects the washing as will be readily comprehended. The washing is produced by the clothing being compressed between the rotary rubber and the positively actuated roller bed. When it is desired to change the water the 20 pipe k' is open and the water drawn off, fresh water being supplied in any desired manner.

Having thus described my invention, what I claim, and desire to secure by Letters Patent, is—

- 25 1. In a washing machine, the combination of a suds box, a series of rollers arranged in approximately a circle to form a roller bed and journaled in the sides of the said suds box, one journal of the rollers projecting on 30 the same side of the said suds box and provided with sprocket pinions, a sprocket wheel journaled on the same side of the suds box with said pinions and provided with a crank,

a sprocket chain connecting the sprocket wheel and sprocket pinions, a lever having 35 pendent arms, and a rotary rubber journaled to the said pendent arms and operated from contact with the said roller bed, substantially as described.

2. In a washing machine the combination 40 with the suds box, and a bed having approximately circular form, of levers pivoted at one end, arms pivotally connected with the said levers, a rotary rubber journaled at its ends to the lower ends of the said arms, and springs 45 between the levers and the said arms, substantially as described for the purpose set forth.

3. In a washing machine, the combination 50 of a suds box, a series of rollers disposed in approximately a circle and journaled at their ends in the side of the suds box, means for positively rotating the said rollers, pivotally supported levers having pendent arms, a rotary rubber journaled at its ends to the said 55 arms and adapted to be operated from the said positively operated rollers, and springs between the pendent arms and the said levers, substantially as described for the purpose set forth.

In testimony whereof I affix my signature in presence of two witnesses.

WILLIAM S. LANEY.
